UNITED STATES PATENT OFFICE.

THEODORE F. ODELL, OF NYACK, NEW YORK.

COMPOSITE ROOFING AND SIDING FOR BUILDINGS.

No. 800,320.

Specification of Letters Patent.

Patented Sept. 26, 1905.

Application filed November 10, 1904. Serial No. 232,233.

To all whom it may concern:

Be it known that I, THEODORE F. ODELL, a citizen of the United States, residing at Nyack, in the county of Rockland and State of New York, have invented certain new and useful Improvements in Composite Roofing and Siding for Buildings; and I do declare the following to be a full, clear, and exact description of the invention; such as will enable others skilled in the art to which it appertains to make and use the same.

This invention relates to improvements in the construction and arrangement of composite material to be used for the roofing and siding of buildings.

The object of the invention is to provide a covering of this character for the roofs and sides of buildings which will be strong, durable, and perfectly waterproof in construction, which may be inexpensively manufactured, and which may be arranged to represent clapboards on the sides of a building.

With the above and other objects in view the invention consists of certain novel features of construction, combination, and arrangement of parts, as will be hereinafter more fully described and claimed.

In the accompanying drawings, Figure 1 is a plan view of a portion of the material, showing the arrangement of the same when used as a side covering. Fig. 2 is a similar view of the material when used as a roof-covering. Fig. 3 is a fragmentary sectional view of Fig. 1. Fig. 4 is a perspective view of a roll of the composite material, showing the manner of packing the same. Fig. 5 is a detail section of the composite sheet.

In the embodiment of the invention I provide a strip or sheet of paper, paper-board, or similar material 1, on one side of which is glued or cemented a layer of muslin or similar fabric 2. To this fabric 2 is applied one or more coats of waterproof paint, by which the material is made impervious to water.

In using the material for roofing purposes the same is applied to the sheathing-boards or roof in a flat strip, as shown in Figs. 2, 4, and 5. When the same is used as a side covering, it is folded upon itself at equidistant intervals, as at 3, thereby forming plaits

which when the material is applied to the sides of the building will run in horizontal rows in semblance to clapboards. When the material is folded upon itself, as just described, a backing in the form of sheets or strips of paper or paper-boards 4 is applied thereto and through the folded portion of the material and said backing-boards are placed rivets 5. Said rivets 5 firmly hold the parts in position and will also present the appearance of the heads of the nails which are used for nailing on clapboards. The addition of the backing-boards give rigidity and strength to the material, thus adapting the same to be more readily applied to the sides of the building.

In applying the muslin or other fabric to the paper-board by means of cement or glue the same will be laid down and smoothly and evenly held in place on the board. The perforating of the board which occurs when the fabric is stitched on is obviated, thus making this form of board more impervious to water.

A material constructed as herein shown and described will be found to be an inexpensive and effective covering for the roofs and siding of buildings which can be quickly and easily applied to the same.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus described my invention, what I claim as new, and desire to secure by Letters Patents, is—

1. A covering of the character described, formed of similar strips of paper and waterproofed fabric cemented together, plaits formed by said strips, and a backing applied to said plaited strips, substantially as and for the purpose described.

2. A covering of the character described, formed of similar strips of paper and waterproofed fabric cemented together, plaits formed by said strips, and a backing of pa-

per, paper-board or the like applied to said plaited strips, substantially as and for the purposes described.

3. A covering of the character described, 5 formed of similar strips of paper and water-proofed fabric cemented together, plaits formed by said strips, a backing of paper, paper-board or the like applied to the inner side of said plaited strips and rivets placed

through said plaits and backing whereby the 10 same are held together and in position, substantially as described.

In testimony whereof I have hereunto set my hand in presence of two subscribing witnesses.

THEODORE F. ODELL.
